UNITED STATES PATENT OFFICE.

CARLETON ELLIS, OF MONTCLAIR, NEW JERSEY, ASSIGNOR TO NATIONAL CARBON COMPANY, OF LONG ISLAND CITY, NEW YORK, A CORPORATION OF NEW JERSEY.

POLYACID-OF-MANGANESE-DIOXID DEPOLARIZER.

1,269,916.

Specification of Letters Patent. Patented June 18, 1918.

No Drawing.

Application filed January 17, 1917. Serial No. 142,926.

To all whom it may concern:

Be it known that I, CARLETON ELLIS, a citizen of the United States, residing at Montclair, in the county of Essex and State of New Jersey, have invented certain new and useful Improvements in Polyacid-of-Manganese-Dioxid Depolarizers, of which the following is a specification.

This invention relates to a depolarizing agent or galvanic cell of the Leclanche type, especially miniature dry batteries such as are commonly employed in pocket flash lights, etc., and relates particularly to the use of polymanganic acid as a depolarizing body, alone, or in conjunction with manganese dioxid, or other higher oxid of manganese depolarizing material and with or without graphite or other species of carbon.

It has been proposed to use manganites as depolarizing agents but these have the disadvantage of containing in many cases an insufficient amount of available oxygen and a body more closely approximating the formula MnO_2 , than that furnished by a manganite is desired. It has also been proposed to employ a product quite different from manganites, namely; certain polymanganites, which while chemically differing from said manganites are not acceptable for all purposes. Further, it has been proposed to use an acid manganous polymanganite as a depolarizing agent.

A disadvantage arising from the use of highly acid manganites or of what may be termed manganous acid, and certain bodies of a related character is that in some cases or under some conditions components of an acid nature, tending to induce local action appear and the zinc electrode of the battery is attacked on standing for a longer or shorter period, depending on the degree of activity of such acid components. The neutralization of the aforesaid manganous acid with bases yields a product more nearly free from this objection but having other disadvantages one of which is the reduced amount of available oxygen over that obtained in pure MnO_2 .

Manganous manganite having the formula $MnO \cdot MnO_2$ (corresponding to the formula Mn_2O_3 , or manganese sesquioxide) contains, as is evident, less oxygen than MnO_2 . On the other hand, the polymanganites, which contain MnO_2 as a radical linked in a cyclic manner have nearly the oxygen con-

tent available for depolarizing purposes, that is obtainable from pure MnO_2 . The corresponding polymanganous acid is practically free from the objections found in compounds mentioned, and furthermore its available oxygen content is still nearer that of pure MnO_2 than salts such as manganous polymanganite.

Polymanganous acid therefore, while being chemically different from said manganous acid has advantages over the latter as a depolarizing agent.

Polymanganous acid may be prepared from one of its salts by acid treatment to remove all or substantially all of the basic matter combined therewith, and may be combined in the form of a brown to black powder which may be incorporated with graphite and molded into the form of a depolarizing mass. Likewise, it may be combined with other forms of manganese dioxid or with such bodies as the manganites or other depolarizing material of a different chemical character, according to the conditions of its use or the requirements of the trade.

While I have mentioned illustratively polymanganous acid as typifying the present invention, it should be understood that I embrace herein the various poly acids of manganese dioxid or similar cyclic or other form of the manganese dioxid radical in poly or plural grouping yielding an acid complex. This application does not, however, include manganous polymanganate or acid manganous polymanganite such as the octa-polymanganite compound described by Kaplan (U. S. Patents 1,109,129 and 1,166,414) but does embrace the free acid liberated from such compounds on removal of the base by a stronger acid.

What I claim is: —

1. A galvanic cell containing free polymanganous acid substantially free from salts of polymanganous acid in the depolarizing mass.

2. A galvanic cell of the Leclanche type containing free polymanganous acid substantially free from salts of polymanganous acid as a depolarizing agent and being substantially free from deleterious local action.

3. A galvanic cell comprising a carbon and zinc electrode and comprising polymanganous acid substantially free from salts

of polymanganous acid as a depolarizing agent, the latter being without substantially any local action on said zinc electrode.

4. A galvanic cell having a depolarizing agent consisting substantially of polymanganous acid substantially free from salts of polymanganous acid.

5. A galvanic cell of the Leclanche type having a depolarizing agent consisting substantially of a poly acid of manganese dioxide substantially free from salts of polymanganous acid.

6. A galvanic cell having a depolarizing agent consisting substantially of an acid washed free poly acid of manganese dioxide substantially free from salts of polymanganous acid.

7. A depolarizing agent consisting substantially of a free poly acid of manganese dioxide substantially free from salts of polymanganous acid.

In testimony whereof I have affixed my signature.

CARLETON ELLIS.
